Des. 219,692
Patented Jan. 5, 1971

219,692

CHILD'S COAT HANGER

Thomas J. Kufchock, 8662 Edna,
Warren, Mich. 48093

Filed Aug. 14, 1969, Ser. No. 18,684

Term of patent 14 years

Int. Cl. D6—07

U.S. Cl. D80—8

In the drawings:

FIG. 1 is a front elevational view of a child's coat hanger embodying my design, the rear of said coat hanger being a mirror image of the front shown; and

FIGS. 2, 3, 4 and 5 are, respectively, top and bottom plan and opposite side views thereof.

What is claimed is:

The ornamental design for a child's coat hanger, as shown and described.
